BUILDING CONSTRUCTION

Harvey W. Schick, Chicago, Ill.

Application January 20, 1934, Serial No. 707,439

6 Claims. (Cl. 72—70)

This invention relates to improvements in building construction and more particularly flat slab constructions suitable for floors, roofs, canopies, landing platforms, balconies and the like where a finished underside is desired, said terms roof, floor, canopy, runways and the like being hereinafter designated as decks for convenience of description.

One object of the invention is to provide a building construction or slab which is fireproof; of minimum weight and thickness consistent with the spans and loads; which is economical not only in the cost of materials but in the labor of fabricating thereof; which will permit of a reduction of the amount of structural steel required in the building; and which permits of certain other advantages during the erection of a building.

More specifically, an object of the invention is to provide a building deck slab construction employing sheet metal sections or pans and a cast filler such as concrete wherein the necessity of temporary forms is eliminated, the slabs being further characterized by the fact that the same provide substantially I beam formations between the structural supporting beams of the building whereby to permit of the use of longer slabs and wider spacing of the supporting means.

Still another object of the invention is to provide a building deck slab construction incorporating novel and effective means for increasing the desirable I beam sections along the junctions of the slabs, to the end that greater load-carrying capacity is obtainable and, further, provision may be made for securing in place, the metal lath for retaining the usual ceiling plaster where the deck construction is finished with a plaster ceiling on its under side.

Other objects of the invention will more clearly appear from the description and claims herein-after following.

In the drawing forming a part of this application, Figure 1 is a broken top plan view of a portion of a roof illustrating one embodiment of the invention. Figure 2 is a vertical, longitudinal, sectional view corresponding to the section line 2—2 of Figure 1. Figure 3 is a transverse, sectional view corresponding to the line 3—3 of Figure 2. Figure 4 is an enlarged, detailed, sectional view illustrating more particularly the formation of the slabs and support for the plaster ceiling. And Figure 5 is a view similar to Figure 4 illustrating another embodiment of the invention.

Referring first to the construction illustrated in Figures 1 to 4 inclusive, 10—10 indicate two of

the supporting beams of the structural framework of a building, the same, in the instance shown, being I beams. In carrying out the deck formation, a plurality of sheet metal pans 11—11 are employed, each of a length sufficient to span the space between the supporting beams 10 and slightly overlie the latter at its ends, as clearly shown in Figure 2. Each of the pans 11, preferably made of sheet steel, is open at each end, has a flat bottom 12 and integral, vertically upstanding sides 13—13. Each of the sides 13 is provided at the top thereof with a horizontally extending integral flange section 14 extending inwardly, that is, toward the center of the pan, each flange section 14 in turn being provided with an integral depending narrower marginal flange 15. As will be understood, each side formation extends the full length of the pan.

Interposed between the sides of each adjacent pair of pans, is a vertically extending plate 16 of greater depth than the depth of the sides 13 and so positioned as to extend both above and below the sides 13, the dependent portion being indicated at 161 and the purpose of which is hereinafter described. The plates 16 will preferably be extended over the supporting beams 10 and across the gaps between the ends of the pans, the plates 16 being cut out or coped as indicated at 162 to straddle the upper flanges of the beams. As will be understood, under those conditions, where a plaster ceiling is not desired, the plates 16 will terminate at their lower edges flush with the bottoms 12 of the pans. At regular intervals, each adjacent pair of pan sides 13 and plate 16 are rigidly secured together by any suitable fastening means, such as the bolts and nuts 17, thus, in effect, making said sides and plates 16 unitary for calculating load-sustaining effect.

As will be evident from the pan and plate formations described, at each junction of the sides of the pans, there is formed, in effect, an I beam in which both sides 13 proper and plate 16 function together as the web; the bottoms 12 of the pans as the lower flanges; and the upper flange sections 14—15 as the upper flanges of the beam. These beams, as evident, extend from supporting beam to supporting beam 10, that is, at right angles to the latter and such I beam formations are spaced apart distances corresponding to the desired widths of the pan forms.

In utilizing the improved construction, the pans 11 are set in place in the building as soon as the steel framework is in place and, to secure said pans in place on the supporting beams, the

pans may be spot welded to the beams 10 at their ends, as indicated at 18-18. In actual practice, the ends of the pans will be slightly separated from each other over the tops of the supporting beams 10, as shown in Figure 2. The pans thus provide a temporary floor while the building is in progress of erection and the various workmen are thereby given a better opportunity to do their work before the concrete filler is poured. The 10 electric conduits may be placed within the pans before pouring the concrete; the outlets properly located and other work done, as will be apparent to those skilled in the art. Furthermore, by being enabled to place the slab pans permanently in 15 position as above described, as soon as the steel framework of the building makes it possible, the builder is enabled to completely enclose the building before the concrete filling is poured, a desirable feature particularly during the winter 20 months when there is danger of the concrete freezing. By welding the slab pans to the supporting beams, relative rocking or vibration between the decking and the steel framework is prevented and also the supporting beams or roof 25 purlins, as the case may be, are laterally braced, as will be apparent.

After the slab pans have been put in place as above described and such other roughing in work of the electricians and the like has been completed, the slab deck construction is then finished by pouring in the concrete. On account of the great strength provided by the I beam formations of the pan structures, as above described, which carry the load stresses from supporting beam to 30 supporting beam, the use of ordinary concrete is unnecessary in most instances, it only being necessary to use a filler that will have sufficient strength to resist crushing under floor loads. For this purpose, a cement is generally employed of 35 that type which produces what is known as an "aerated" concrete, that is, a concrete very much lighter per unit of volume than ordinary concrete mixtures. The cement for such aerated concrete is of that character such that, when 40 water is added thereto, the water is decomposed and produces gases that in turn produce voids or air bubbles in the concrete mix. Ordinarily, such concrete mixtures are poured in a very wet or 45 sloppy condition to about one half the desired depth of the completed filler. When dehydration takes place, the mix expands to about twice 50 its original volume. It is then permitted to set and, if necessary, the exposed surface of the filler is shaved off and, in the particular construction 55 shown, such concrete 19 will be shaved off flush with the upper edges of the web plates 16. In the completed slab construction, it will be seen that the flange sections 14 and their marginal flanges 15 are imbedded in the concrete, thus 60 reinforcing the latter and providing an extremely strong but relatively light deck formation. As 65 will be apparent from Figure 2, the concrete is made continuous from one slab pan to the other, due to the open ends of the pans.

Where a plaster ceiling is desired, the metal lath therefor, indicated at 20, will be attached to the dependent portions 161 of the web plate 16 as 70 by wire loops 21 passed through suitable openings 22 provided at intervals along the dependent section 161, as clearly shown in Figure 4. The plaster 23 is then applied to the lath, thus leaving an air space 24 between the bottom of the deck proper and the plaster ceiling, the web plate 16 thus providing simple means for applying such ceilings.

Referring next to the construction illustrated in Figure 5, the pans 211-211 are of the same general construction as those illustrated in Figures 1 to 4. In forming the pans of the Figure 5 construction, however, the side walls 213-213 thereof are preferably initially deflected slightly from a true right angle position relative to the bottoms 211 as shown, particularly if the gauge of the metal is at all heavy. This is to permit of the ready insertion of a plate 216 of lesser 10 depth than the plates 16. The plates 216 are left extended above the top flanges 214 of the pans, as shown, and are preferably extended downwardly between the side walls 213 for approximately the same distance as exposed above 15 the flanges 214. In this construction, the plates 216 are spot welded at intervals to the pans as indicated at 316, thus providing a unitary construction between each plate 216 and two pans for calculating loads. As will be understood, before the plates 216 are inserted, the pans will be secured together through their side walls by means of bolts and nuts 217 which, as the plates 216 are wedged down into place, function substantially as fulcrum points, insuring a closer 25 union or joint at the bottoms of the pans as indicated at 317. Preferably also, a small amount of mastic paint or equivalent is inserted between the slightly flaring side walls of the pans below the plates 216 to insure a closed joint and prevent undesirable seepage of the filler down through the joint when the filler is poured in place. The plates 216 will also preferably be extended continuously from one set of pans over the supporting beams as in the case of the plates 30 16 previously described so as to insure a better tension factor over the beams against any possible deflection of the slabs intermediate the supporting beams. The filler will be preferably of the same character as that described for the 35 construction of Figures 1 to 4 and poured in the same manner, thus insuring a strong but relatively light deck construction.

Where either of the constructions shown in Figures 4 or 5 are employed as a floor and it is 45 desired to finish the same with terrazzo, the upwardly extended portions of the plates 16 or 216 as the case may be, effectively serve as the spacing strips usually employed with terrazzo finishes.

The improved slab construction has been 50 described with particular reference to its employment as decking in buildings but, as will be obvious to those skilled in the art, the improvements may be incorporated in vertical or side walls of buildings with equal economy and advantages. 55

From the preceding description, it will be seen that the improved slab construction may be made of relatively light weight; is compact; neat in appearance; resistant to transmission of heat and sound, the latter particularly on account of the 60 aerated concrete filler; and is completely fire resistant.

What is claimed is:

1. A building deck construction including: spaced supporting beams; a plurality of deck-forming slabs extending transversely between and supported on the beams, each slab comprising a sheet metal pan with a bottom, longitudinally up-standing sides and a cast filler; and a vertically disposed beam-web-functioning plate interposed 65 between and welded to each adjacent pair of pan sides, said plate being extended above the pan sides and having its lower edge located intermediate the tops and bottoms of the pan sides.

2. A building deck construction including: 70

spaced supporting beams; a plurality of deck-forming slabs extending transversely between and supported on the beams, each slab comprising a sheet metal pan with a bottom, longitudinally upstanding sides and a cast filler; a vertically disposed, beam-web-functioning plate interposed between each adjacent pair of pan sides, said plates extending downwardly below the bottoms of the pans, the extended portions being adapted to provide means for supporting and attaching ceiling lath; and means rigidly uniting each said plate and corresponding adjacent pan sides.

3. A building deck construction including: spaced supporting beams; a plurality of deck-forming slabs extending transversely between and supported at their ends on said beams, each slab including an open ended sheet metal pan with a flat bottom, longitudinally extending upstanding sides, each of the latter having an integrally formed flange section at the top and each flange section formed with an integral marginal flange; a vertically disposed beam-web-functioning plate interposed between and rigidly secured to each adjacent pair of pan sides and extending above and below the pans; and concrete filler for the pans extending above said flange sections and flush with the upper edges of said plates.

4. A building deck construction including: a series of spaced parallelly arranged supporting beams; a plurality of slab pans supported and secured at their ends on said beams, said pans being arranged side by side and those between one pair of beams being alined with those between adjacent sets of beams, each pan having a bottom and integral, longitudinally extending upstanding sides, the latter having relatively wide flange sections extending toward each other and the pans being open at their ends; vertically disposed

beam-web-functioning plates interposed between each adjacent pair of pan sides, said plates extending across the supporting beams; means rigidly uniting adjacent pairs of pan sides and said plates to the pan sides; and cast fillers in the pans extending continuously throughout the lengths of the pans from one alined pan to another and within which fillers said flange sections are imbedded.

5. A building deck construction including: spaced supporting beams; a plurality of deck-forming slabs extending transversely between and supported at their ends on the beams, each slab comprising a sheet metal pan with a bottom, longitudinally extending upstanding and inwardly flanged sides, and a cast filler; means rigidly uniting adjacent pairs of pan sides; and a vertically disposed beam-web-functioning plate interposed between adjacent pairs of pan sides, each said plate extending partially above and partially below the flanged sections and rigidly united to the pans, said flange sections and upwardly extended portions of the plates being imbedded within the cast fillers.

6. A building construction including: a plurality of formed sheet metal pans arranged side by side, each pan being open at its ends and having a flat bottom and longitudinally extending sides flanged inwardly toward each other; beam-web-functioning plates interposed between adjacent pairs of pan sides, said plates having portions thereof extending beyond the flanges in a direction away from the pan bottoms; means rigidly securing said plates to the respective pairs of pan sides; additional means rigidly securing the pan sides together; and cast fillings within the pans and within which the flanges and extended portions of the plates are imbedded.
